FRANK E. SEELEY, OF BRIDGEPORT, CONNECTICUT, ASSIGNOR TO THE PERKINS ELECTRIC SWITCH MFG. COMPANY, OF BRIDGEPORT, CONNECTICUT, A CORPORATION OF CONNECTICUT.

PENDENT ELECTRIC SWITCH.

962,923.

Specification of Letters Patent. Patented June 28, 1910.

Application filed September 4, 1908. Serial No. 451,678.

To all whom it may concern:

Be it known that I, FRANK E. SEELEY, a citizen of the United States of America, and residing at Bridgeport, in the county of 5 Fairfield and State of Connecticut, have invented a certain new and Improved Pendent Electric Switch, of which the following is a specification.

The object of my invention is to provide 10 a simple and economically manufactured construction of pendent electric switch, more particularly of the single push button type. This object I attain by the construction which I will now describe.

15 In the accompanying drawing, Figure 1 is a vertical section on the line 1—1, Fig. 3; Fig. 2 is a section on the line 2—2, Fig. 3; Fig. 3 is a section on the line 3—3, Fig. 1; Fig. 4 is a sectional view on the line 4—4, 20 Fig. 3; and Fig. 5 is a perspective view of some details separated.

The body of the switch consists of a cup A of porcelain or other suitable insulating material, with its open end downward, and 25 its upper end closed except for certain holes formed for the passage of the terminal plates and the holes for the securing screws. The moving parts of the switch mechanism are inclosed within this inverted cup 30 and are wholly mounted upon a frame F, formed out of sheet metal stamped out and with certain parts bent into flanges. Thus there are two flanges f, f, threaded to receive the threaded ends of securing screws 6, 6, 35 passing through holes in the porcelain cup from the outside thereof. These screws are the means for firmly securing the switch frame and the moving parts thereon to the insulating body A. This frame F has a central extension 7, passing through a hole in the top of the cup body and provided outside with a binding screw 8, thus constituting a terminal plate for one of the line wires.

On a flange 9 at the lower end of the 45 frame plate is secured a bent spring contact 10, to bear against the ratchet contact wheel C, for the making and breaking of the circuit.

In the present instance I have shown the 50 switch as constructed for connection to three wires and so that the circuit may be closed either through one pair of wires, all three wires or no circuit. Diametrically opposite the contact spring 10 are arranged two

spring contacts 11 and 12 in the upper part 55 of the cup, and connected with terminal plates 13, 14, projecting out through openings in the top of the cup and provided on the outside with binding screws for the wires. 60

The make and break wheel C may be of any suitable construction, but I prefer to make it as shown of a body of insulating material with a metallic plate 15 secured across one face and bent down over the peripheral edges of four out of the six teeth of the ratchet, as shown. This ratchet wheel C is mounted to turn upon a center pin 20 secured to the frame F and has secured to one face a side ratchet plate 16, Figs. 3 and 70 5. With this ratchet plate co-operates an actuating pawl plate 17, mounted to oscillate upon the center pin 20, and normally held up against the ratchet plate 16 on the wheel C by a spring washer 18. On the 75 actuating pawl plate 17 is a crank pin 19, entering a cross slot 21 in the push plate P, which is vertically guided partly by the center pin 20 passing through a vertical slot in the push plate (Fig. 4) and partly by the 80 passing of the lower stem of the push plate through a slot in the flange 9 of the frame F. To the lower end of this push plate is secured a push button p, and a spiral spring 22, interposed between the flange 9 of the 85 frame and this button p, returns the push button and plate to the normal position shown in Figs. 1, 2 and 3, after each upward pressure, and with each such upward pressure, the make and break wheel C will be 90 turned to the extent of one tooth, as will be readily understood. By suitable changes in this ratchet wheel and spring contacts, various make and break connections may be made. I provide a hole a in the side of the 95 inverted cup for inspection and adjustment of the upper contact springs.

By the described construction of pendent switch having an insulating body of an inverted cup shape with the terminal plates 100 passing through from the inside to the outside, I provide a strong switch with the mechanism well protected from the stray strands of the connected wires.

The whole may be inclosed in any usual 105 or convenient metal shell S, Fig. 1.

I claim as my invention:

1. A pendent electric switch, comprising

an inverted cup of insulating material, a push button switch mechanism therein, embracing a push button at the bottom, a ratchet wheel and contacts, and a frame in which said mechanism is wholly mounted, said frame having a terminal plate passing through the top of the inverted cup, substantially as described.

2. A pendent electric switch, comprising an inverted cup of insulating material, a push button switch mechanism therein embracing a push button, a make and break ratchet wheel and spring contacts, a frame in which said switch mechanism is wholly mounted, the frame carrying one spring contact and having a terminal plate passing through the top of the inverted cup, in combination with another terminal plate also passing through the top of the cup and con-

nected with another spring contact within 20 the cup.

3. A pendent electric switch, comprising an inverted cup of insulating material, a push button switch mechanism therein, embracing a make and break wheel, two contacts carried by the insulation, a supporting frame also secured to the latter and having a contact for the make and break wheel, a ratchet plate on the latter, a push plate, pawl plate and return spring. 30

In testimony whereof I have signed my name to this specification, in the presence of two subscribing witnesses.

FRANK E. SEELEY.
